Patented Mar. 23, 1976

239,249

INSULATED FOOD CONTAINER

Tony E. Branscum, Winfield, Kans., assignor to
Gott Manufacturing Co., Inc.

Filed Oct. 15, 1974, Ser. No. 514,832

Term of patent 14 years

Int. Cl. D7—07

U.S. Cl. D7—77

Fig. 1.

Fig. 4.

Fig. 2.

Fig. 5.

Fig. 3.

FIG. 1 is a top perspective view of an insulated food container showing my new design;

FIG. 2 is an elevational view thereof showing the side opposite that shown in FIG. 1;

FIG. 3 is a top plan view thereof;

FIG. 4 is an elevational view thereof showing the end opposite that shown in FIG. 1; and

FIG. 5 is a bottom plan view thereof.

I claim:

The ornamental design for an insulated food container, as shown.
